UNITED STATES PATENT OFFICE

ERNEST W. FREUDENBERG, OF LARCHMONT, NEW YORK

DESIGN FOR AN EMBROIDERED TEXTILE FABRIC OR A SIMILAR ARTICLE

Application filed October 18, 1932. Serial No. 45,392. Term of patent 3½ years.

To all whom it may concern:

Be it known that I, ERNEST W. FREUDENBERG, a citizen of the United States, residing in Larchmont, county of West Chester, State of New York, have invented a new, original, and ornamental Design for an Embroidered Textile Fabric or a Similar Article, of which the following is a specification, reference being had to the accompanying drawing, forming part thereof.

The figure is a plan view of an embroidered textile fabric or a similar article, showing my new design.

The dot and dash lines on the drawing outline the design unit, which unit is repeated in regular succession, as indicated by the extensions beyond the unit boundaries. The design consists essentially of a sinuous intertwining and continuous stem and a flower and leaf arrangement combined with a colbert background.

I claim:

The ornamental design for an embroidered textile fabric or a similar article substantially as shown and described.

ERNEST W. FREUDENBERG.
